COMBINED BOOK AND FIGURINE PACKAGE

Violet A. Sikking, Fallbrook, Calif.

Application November 23, 1953, Serial No. 27,723

Term of patent 7 years

(Cl. D58—12.6)

Fig. 1

Fig. 4

Fig. 3

Fig. 2

I claim:

The ornamental design for a combined book and figurine package, as shown.
